UNITED STATES PATENT OFFICE.

SWINFEN BRAMLEY-MOORE, OF WHITE PLAINS, NEW YORK.

CRUSHING, GRINDING, AND REFINING MACHINE.

Application filed April 6, 1928. Serial No. 267,992.

The present invention relates to crushing, grinding and refining machines, such as are used for crushing, grinding or refining chocolate, paint, printer's ink and other materials, and the general object of the invention is to provide a machine of that kind which is improved throughout to increase the efficiency thereof.

Another object of the invention is the provision of novel crushing, grinding or refining elements.

A further object is to provide novel means for mounting the grinding elements and to provide novel means for applying pressure 15 to said elements.

A still further object is to provide novel means for feeding or directing the material to the grinding elements.

The invention has for another object the provision of novel mechanism for controlling and regulating the pressure of the grinding elements, which may be operated during the 20 operation of the machine.

With the foregoing and other objects in view, which will be apparent as the description proceeds, the invention resides in the construction and arrangement of parts as hereinafter described and claimed, it being understood that changes can be made within 30 the scope of what is claimed, without departing from the spirit of the invention.

The invention is illustrated in the accompanying drawings, wherein—

Figure 1 is a vertical median section of the machine, portions being shown in elevation, and portions being omitted and broken away for sake of clearness.

Fig. 2 is an enlarged sectional detail on the line 2—2 of Fig. 1.

Fig. 3 is a plan or face view of one of the grinding units on an enlarged scale.

Fig. 4 is a sectional detail on the line 4—4 of Fig. 3.

Fig. 5 is a detail view illustrating the dynamometer for indicating the pressure.

The casing comprises the cylindrical body 11 and end plates 12 and 13, said end plates having the inlets 14 near the top of the casing which is disposed with its axis horizontal, and the end plates have the hoppers 15 into which the material is dumped to flow through the inlets into the casing. A water jacket 16 surrounds the body 11 for the circulation of

water therein to cool the body, or conversely for the circulation of a heating medium.

The body 11 has a liner 17, which may be composed of sections or arcuate plates, and said liner may be of chilled cast iron, carbide, tool steel or other suitable material to provide an effective grinding surface. The inner surface of the liner 17 is provided with small ribs 18 which are preferably parallel with the axis of the casing, and which assist in the crushing, grinding and refining action as the grinding elements move along the surface of the liner.

The end plate 13 has a normally closed outlet 19 near the bottom of the casing, through which the material may be discharged.

The end plate 12 has a bearing 20 extending 70 within the casing centrally thereof, and through which a tubular or sleeve shaft 21 is journaled, and a shaft 22 extends through the shaft 21. A wheel 23 is secured on the inner terminal of the shaft 21 between the end plates of the casing to move the grinding elements along the grinding surface of the casing.

In order to mount the grinding elements 80 on the wheel 23, levers 24 are provided which have the short arms 25 projecting beyond the periphery of the wheel, and said levers are mounted on shafts or pivots 26 carried by the wheel. Said levers have long arms 27 extending 85 inwardly and provided with rounded terminals 28 working within slots 29 in a disk 30 secured on the inner terminal of the shaft 22, so that the levers 25 may be swung on their pivots by the rotation of the disk 30 relatively to the wheel 23.

The grinding elements are arranged in groups, and a plurality of grinding units are provided each including a group or set of grinding elements.

The lever arms 25 have bearings 31 through 95 which rods 32 extend parallel with the axis of the casing and located near the grinding surface of the liner 17. Each rod 32 carries several (five as shown) of the grinding units which are arranged end to end longitudinally 100 of the casing, as seen in Fig. 1. Each grinding unit comprises a pair of laminated leaf springs 33 secured between their ends to blocks 34 loosely mounted on the corresponding rod 32, and the opposite ends of the springs 105 are bent into bearings 33' embracing rods 35.

parallel with the rod 32. There are two rods 35 in each grinding unit, and a pair of cross members 36 is mounted for oscillatory motion on each rod 35.

5 The members 36 of each pair have notches or recesses 37 extending through more than one-half of a circle, in which the grinding elements 38 are fitted. Said grinding elements are of circular cross-section, as shown, 10 and may be moved endwise into and out of the recesses 37 in assembling and separating the parts. The grinding elements or rods 38 may be of tool steel, carborundum, metal or other suitable material, and present rounded 15 grinding surfaces to the grinding surface of the liner 17 for effectively grinding, crushing or refining the material. The grinding elements are located in front and in rear of the corresponding rods 35, whereby the outward pressure of the springs 33 is distributed 20 equally to the grinding elements, and the cross members or carriers 36 may rock with the rods 35 about the spring eyes 33' as the pivot axis to enable the grinding elements to 25 pass across lumps or clods of material with a yielding action. Thus, either grinding element of a pair may move away from the liner 17, and both grinding elements are under substantially equal pressure. The 30 grinding elements 38 are disposed end to end throughout the length of the body 11, as seen in Fig. 1.

In order to retain the grinding elements 38 in place, they are provided with apertures 35 39 therein, to receive the terminals 40 of wire retaining elements having the loops 41 between said terminals fitted on the rods 35.

When the wire retaining elements 40, 41 are disengaged from the grinding elements, 40 such elements may be turned in the recesses 37 and the retaining elements again engaged 45 with said grinding elements, in order that the grinding elements may be used for an extended period of time. Thus, after the elements 38 wear down flat, they may be loosened and turned to present other curved surfaces thereof to the liner, and this may be repeated several times until the grinding elements are worn away.

50 In order to feed or direct the material between the grinding elements 38 and the liner 17, feed or deflecting plates 42 are disposed in front of the grinding elements between the members 36, and are hingedly mounted in 55 front of the corresponding grinding elements. The rear plate 42 of each pair has its forward edge bent into a sleeve 42' loosely embracing the corresponding rod 35, and a rod 35' is mounted in each pair of members 36 at the forward ends thereof and is loosely embraced by a sleeve 42' of the front plate 42. The plates 42 may thus turn on the rods 35, 35', and the rear edges of said plates contact with the grinding elements 38. As 60 shown, wire springs 42'' have coils embracing

the rods 35, 35', with their terminals contacting with the plates 42 and grinding elements to hold said plates against said elements, but these springs, in some cases, may be omitted. The plates 42 have slots to accommodate the 70 springs.

The hub of the wheel 23 has a scraper 43 extending toward the end plate 12 and movable around the bearing 20 in order to scrape the material from said bearing and thereby 75 prevent the material accumulating thereon.

The machine is driven by a gear wheel 44 secured on the outer terminal of the shaft 21 and located within a housing 45 carried by the end plate 12, and a bearing 46 is carried 80 by the housing 45 beyond the end of the shaft 21 in which a tubular or sleeve shaft 47 is mounted for rotation. The shaft 47 has a flange 49 between the bearing 46 and wheel 44 and an anti-friction thrust bearing 48 85 is disposed between the inner end of the bearing 46 and said flange 49, to take up the axial thrust in one direction. The inner end of the shaft 47 has a flange 50 secured to the hub of the wheel 44, whereby the shafts 21 90 and 47 are driven by said wheel. The shaft 22 extends through the shaft 47 as well as the shaft 21.

The outer terminals of the shafts 22 and 47 are operably connected to obtain relative 95 rotation thereof in order to regulate the pressure of the springs 33. For this purpose planetary gearing is housed within a case 51 including the cylindrical body 52 disposed between the heads or plates 53 and 54. Bolts 100 or tie rods 55 extend through said heads and have flanged washers 60 thereon bearing against the inner head 54 and overlapping an outstanding annular flange 59 on the hub of a hand wheel 56 which is screw-threaded, 105 as at 57, on the bearing 46.

The case 51 and hand wheel 56 thus have a swivel connection whereby they are free to rotate relatively to one another, and the case is movable longitudinally with the hand wheel. An anti-frictional thrust bearing 58 is confined between the head 54 and hub of the hand wheel 56 to take up the end thrust opposite to that taken up by the bearing 48. The bearing 48 takes up pressure from the 110 shafts 21, 22 and 47, while the bearing 58 takes up the opposite end thrust on said shaft.

The head 54 is rotatable on the shaft 47, while the head 53 is rotatable on the sleeve 61 on the outer terminal of the shaft 22. The 115 sleeve 61 may be graduated to indicate thereon the position of the case 51 and hand wheel 56 longitudinally of the shaft, it being apparent that the marks on the sleeve 61 are covered up and exposed, respectively, as the case 120 51 is moved outwardly and inwardly on the shafts.

The planetary gearing within the case 51 comprises sun gears 62 and 63 secured on the shafts 22 and 47, respectively, and planet 125 65

gears 64 and 65 meshing with the gears 62 and 63, respectively. There are preferably two or more pairs of gears 64, 65 and each pair is secured on a sleeve 66 rotatable on a rod 55.

The gears 64 and 65 have spiral or oblique teeth in reverse arrangement, and the teeth of the gears 62 and 63 are correspondingly arranged, so that the sliding movement of the gears 64, 65 with respect to the gears 62, 63, respectively, will result in relative turning movements of the shafts 22 and 47, 21. This action occurs with the parts stationary excepting for axial sliding motion, with the case 15 51 rotating with the shafts, or with the case stationary while the shafts are rotating. When the case 51 is slid longitudinally the sliding movement of the gears 64, 65 with reference to the gears 62, 63 will, by the helical 20 angle of the gear teeth, tend to rotate the gears 62, 63 in opposite direction, thereby similarly turning the shafts 22 and 47, 21 relatively to one another.

In this manner, the shaft 22 is turned in the shaft 21 to turn the disk 30 relatively to the wheel 23, thereby swinging the levers 25, and by adjusting the hand wheel 56 the levers 25 may be swung to force the rods 32 either outwardly or inwardly to increase or decrease 30 the pressure on the springs 33 and grinding elements 38. The levers 25 are non-yielding in any adjustment thereof, so that the mountings of the leaf springs 33 are non-yieldable, thereby maintaining the intermediate portions 35 of the leaf springs at a fixed distance from the grinding surface of the casing in any particular adjustment of the levers.

The case 51 is free to rotate with the shafts, during the operation of the machine, but the 40 case may be held against rotation, in which event the gears 64, 65 will rotate about their own spindles, whereas when the case turns with the shafts the gears 64, 65 rotate solid with the gears 62, 63. The planetary gearing 45 thus affords effective means for obtaining relative rotation of the wheel 23 and disk 30, to regulate the pressure on the grinding elements, and the gearing operates with a minimum friction and resistance.

50 The planetary gearing may also be employed as dynamometer, either in connection with the crushing, grinding or refining machine, or in connection with any other machine or between relatively rotatable shafts or members. Thus, as seen in Fig. 5, an arm 67 may be carried by the case 51, to which a suitable spring 68 is connected, and said arm operates with a suitably graduated scale 69. The case 51 has a tendency to be rotated in 55 one direction with the shafts, which is resisted by the spring 68. The greater the pressure or resistance is between the shafts, the greater will be the force tending to turn the case 51 and arm 67, so that the load is indicated on the scale 69. It is thus possible to use

the planetary gearing as a dynamometer in connection with the machine disclosed herein or for general purposes. With this arrangement the arm 67 will indicate on the scale 69 the pressure between the grinding 70 elements 38 and grinding surface along which they move.

The grinding elements 38 are preferably of circular cross-section, but may be of square or other polygonal cross-section, in which 75 event the recesses 37 are of corresponding form.

Having thus described the invention, what is claimed as new is:—

1. A machine of the character described comprising a cylindrical casing having a grinding surface therein, two shafts, a wheel on one shaft within the casing, levers carried by said wheel, a disk mounted on the other shaft and operably connected with said levers, grinding elements carried by said levers and working along said grinding surface, and means operably connecting said shafts for rotating one with the other and for adjusting them rotatably relatively to one another 80 to swing said levers relatively to said wheel and regulate the pressure on said grinding elements.

2. A machine of the character described comprising a casing having a grinding surface therein, a tubular shaft entering the casing, a wheel secured on said shaft within the casing, grinding elements carried by said wheel to work along said grinding surface, a second shaft extending through said tubular shaft, and operative connection between said second shaft and grinding elements to move said grinding elements along said surface, by the rotation of the second shaft relatively to the tubular shaft, and an operative connection between said shafts for turning the second shaft with the tubular shaft and adjusting the shafts rotatably relatively to one another. 95

3. A machine of the character described comprising a casing having a grinding surface therein, a wheel mounted for rotation in said casing, levers carried by said wheel, leaf springs connected between their ends with said levers, grinding elements connected with the end portions of said springs and working along said grinding surface, and means for swinging said levers relatively to said wheel to regulate the pressure on said springs and grinding elements. 100

4. A machine of the character described comprising a casing having a grinding surface, and grinding means working within the casing including leaf springs, grinding elements carried by the end portions of said springs and working along said surface, and means for applying non-yielding pressure to the intermediate portions of the springs. 115

5. A machine of the character described comprising a casing having a grinding sur-

face therein, a wheel mounted for rotation within the casing, non-yieldable adjustable members carried by the wheel, leaf springs mounted between their ends on said members, and grinding elements carried by the end portions of said springs and working along said surface.

6. A machine of the character described comprising a casing having a grinding surface therein, and grinding means rotatable within the casing and including carrier members having recesses, and rod-shaped grinding elements disposed in said recesses and adapted to be positioned therein to present different surfaces thereof to said grinding surface.

7. A machine of the character described comprising a casing having a grinding surface therein, a wheel rotatable within the casing, adjustable pressure members carried by said wheel, carrier members hingedly connected between their ends with said pressure members, and having recesses in front and in rear of the hinge connections, and grinding elements in said recesses and working along said grinding surface.

8. A machine of the character described comprising a casing having a grinding surface therein, a wheel rotatable in the casing, adjustable members carried by the wheel, leaf springs mounted between their ends on said members, rods carried by the end portions of said springs, carrier members mounted between their ends on said rods, and grinding elements mounted in said carrier members in front and in rear of said rods.

9. A machine of the character described comprising a casing having a grinding surface therein, and a rotatable grinding means within said casing having grinding elements working along said surface and feed plates in front of said elements to feed the material between said elements and surface.

10. A machine of the character described comprising a casing, a wheel rotatable therein, carrier members mounted on said wheel and having recesses, grinding elements disposed in said recesses, rods carried by said members and feed plates hingedly mounted on said rods in front of the grinding elements and extending rearwardly to said elements to direct the material between said elements and casing.

11. A machine of the character described comprising a casing having a grinding surface, a wheel mounted for rotation in said casing, levers carried by said wheel, means for swinging said levers relatively to said wheel, rods carried by said levers, leaf springs mounted between their ends on said rods, carrier members hingedly mounted between their ends to the end portions of said springs and having recesses in front and in rear of the hinge connections, and rod-like grinding elements disposed in said recesses and working along said grinding surface.

12. A machine of the character described comprising a casing having a grinding surface, a wheel mounted for rotation in said casing, levers carried by said wheel, means for swinging said levers relatively to said wheel, rods carried by said levers, leaf springs mounted between their ends on said rods, carrier members having front and rear recesses, rod-like grinding elements disposed in said recesses and working along said grinding surface, rods carried by said carrier members in front of said grinding elements, the rear rods being hingedly mounted on the end portions of said springs, and feed plates hingedly mounted on said rods and extending rearwardly to said grinding elements.

13. A machine of the character described comprising a cylindrical casing, two shafts, a wheel on one shaft within the casing, levers carried by said wheel, grinding elements carried by said levers and working within said casing, means for turning said shafts with reference to one another, and operative connections between the other shaft and said levers to regulate the pressure on said elements by the relative turning adjustment of said shafts.

14. A machine of the character described comprising a casing having a grinding surface therein, a wheel mounted for rotation within the casing, adjustable members carried by said wheel, leaf springs mounted between their ends on said members, carrier members hingedly connected with the end portions of said springs, and grinding elements carried by said carrier members in front and in rear of the hinge connections and working along said grinding surface.

15. A machine of the character described comprising a casing having a grinding surface, two shafts, a member secured to one shaft within said casing, grinding elements mounted on said member to work along said surface, operative connections between the other shaft and said elements to apply pressure to said elements by relative rotation of said shafts, and gearing connecting said shafts for rotating one with the other and including relatively slideable spiral gears for turning one shaft relatively to the other.

16. A machine of the character described comprising a casing having a grinding surface, two shafts, a member secured to one shaft within said casing, grinding elements mounted on said member to work along said surface, operative connections between the other shaft and said elements to apply pressure to said elements by relative rotation of said shafts, and planetary gearing connecting said shafts for the rotation of one shaft with the other and including relatively slideable spiral gears for rotating one shaft relatively to the other.

17. A machine of the character described

- comprising a casing having a grinding surface, two shafts, a member secured to one shaft within said casing, grinding elements mounted on said member to work along said surface, operative connections between the other shaft and said elements to apply pressure to said elements by relative rotation of said shafts, and planetary gearing including spiral sun gears rotatable with said shafts and spiral planet gears rotatable one with the other and meshing with the sun gears, the sun and planet gears being slidable longitudinally of the shafts relatively to one another for turning one shaft relatively to the other.
- 5 18. A machine of the character described comprising a casing having a grinding sur-
- face, two shafts, a member secured to one shaft within said casing, grinding elements mounted on said member to work along said surface, operative connections between the other shaft and said elements to apply pressure to said elements by relative rotation of said shafts, a case rotatable and slidable on said shafts, spiral sun gears secured on said shafts, spiral planet gears rotatable one with the other, carried by said case and meshing with said sun gears, and means for sliding said case on said shafts.
- 10 15 In testimony whereof I hereunto affix my signature.

SWINFEN BRAMLEY-MOORE.
